Primary Examiner — Mary Ann Calabrese*Assistant Examiner* — Natalya M Rapundalo(74) *Attorney, Agent, or Firm* — Dinsmore & Shohl LLP(57) **CLAIM**

I claim the ornamental design for a steam oven, as shown and described.

DESCRIPTION

FIG. 1 is a front, right and top side perspective view of a steam oven showing my new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of portion 9 encircled in FIG. 2. The broken lines shown in the drawings represent portions of the steam oven that form no part of the claimed design.
